Patented Jan. 27, 1976

238,535

DISPLAY RACK FOR BOTTLES OR THE LIKE

Fitz Daniels, 21 St. James Place,
Brooklyn, N.Y. 11205

Filed June 19, 1974, Ser. No. 480,611

Term of patent 14 years

Int. Cl. D20—02

U.S. Cl. D6—189

FIG. 2

FIG. 1

FIG. 3

FIG. 4

FIG. 5

FIG. 1 is a front perspective view of a display rack for bottles or the like, showing my new design;

FIG. 2 is a front elevational view thereof;

FIG. 3 is a type plan view thereof;

FIG. 4 is a side elevational view thereof; and

FIG. 5 is a rear elevational view thereof.

I claim:

The ornamental design for a display rack for bottles or the like, substantially as shown.
